UNITED STATES PATENT OFFICE

DENYS W. CORBET, OF NEW YORK, N. Y., ASSIGNOR, BY MESNE ASSIGNMENTS, TO AUTOSALES GUM AND CHOCOLATE COMPANY, OF NEW YORK, N. Y., A CORPORATION OF NEW YORK.

AUTOMATIC COIN-OPERATED LOCK.

1,154,381.

Specification of Letters Patent. Patented Sept. 21, 1915.

Application filed November 12, 1910, Serial No. 591,971. Renewed March 2, 1912. Serial No. 681,251.

To all whom it may concern:

Be it known that I, DENYS W. CORBET, a subject of the King of Great Britain, and a resident of the borough of Brooklyn, 5 county of Kings, city and State of New York, have invented certain new and useful Improvements in Automatic Coin-Operated Lock, set forth in the following specification.

10 This invention relates to a coin controlled lock for a receptacle adapted to contain a single package which is to be vended automatically upon the insertion of the proper coin.

15 An object of the present invention is to effect the automatic unlocking of such a vending receptacle by the mere insertion of the proper coin into an appropriate slot or opening and entirely without the manual 20 manipulation of any knob, slide or part other than the actual coin inserted.

25 A further object of the invention is to retain the inserted coin within the locking mechanism and to prevent its unauthorized removal.

30 A still further object of the invention is to provide for the removal of the inserted coin from the locking mechanism and the contemporaneous restoration of the parts to their normal positions in a manner necessitating the use of a key and special manipulation.

35 In addition a general object of the invention aims to simplify coin controlled locks for vending receptacles of the class described.

40 To the above ends a locking latch bolt is provided for holding the openable part of the receptacle locked closed; a coin slot; a spring operated coin carrier in coöperative relation with said coin slot; a latch mechanism for releasing the coin carrier upon the insertion of the proper coin; and measuring means permitting the spring operated 45 travel of the coin carrier upon the insertion of the proper coin only; means for closing the coin slot after the insertion of the proper coin; means for locking the coin carrier against movement to discharge the inserted 50 coin and to lock the closure for the coin slot in closed position; and provisions for retaining the locking latch bolt or bolts in retracted position.

A still further object of the invention is

to provide substantially a combination lock, 55 the correct manipulation of which is necessary to accomplish the removal of a coin, to the end that an unauthorized person merely provided with the proper unlocking key will be unable to remove an inserted coin 60 unless he is familiar with the further necessary manipulation.

The above and further objects of the invention will be set forth more fully in the accompanying claims and will be understood 65 from the following specification which should be read in connection with the accompanying drawings which form a part of this application, in which like characters designate corresponding parts and in 70 which,—

Figure 1 is a front elevation of a dispensing receptacle with parts broken away and others in section, fitted with the invention; Fig. 2 is a vertical section through line 75 II—II of Fig. 1; Fig. 3 is a plan view of the structure of Fig. 1; Fig. 4 is a vertical front elevation corresponding to Fig. 1 but with the outer face of the receptacle removed and showing merely the locking parts about to 80 be operated upon by a coin; Fig. 5 is a view similar to that of Fig. 4 but with parts broken away and showing the relative positions of the parts assumed immediately upon the insertion of the coin; Fig. 6 is also a 85 view similar to Fig. 4 showing the position of the parts assumed immediately after the coin has been completely inserted; Fig. 7 is also a view similar to Fig. 4 showing the necessary relative positions of the parts to 90 permit the discharge of the coin; and Fig. 8 is a perspective view showing the key.

Referring now more in detail to the drawing,—1 designates the dispensing receptacle which may be of any suitable construction, 95 but is shown comprising a sheet metal stamping 2 forming the front, sides and bottom of a box and flanged at the rear to slide into the channel 3 formed along the two side edges and bottom edge of a sheet 100 metal back plate 4, which may be secured to the back of a theater chair or other support in a well known manner. The stamping 2 may be releasably secured to the back plate 4 by the lock and key 65, 66. The top 105 of the receptacle 1 is provided with the openable lid 5 secured by the hinge 6 along its rear edge to the metal stamping 2 and pro-

vided with a downward projection 7 co-operating with a tongue 8 formed by vertically slitting the back plate 4 to form a spring tongue tending to open the lid 5. 5 The lid 5 is closed and locked over the mouth of the receptacle 1 when charged with a package, such as 9, to be vended. A spring 10 at the bottom of the receptacle 1 may serve normally to press the package 9 upward to cause it to project out of the receptacle 1 upon the unlocking and opening of lid 5. Although this receptacle 1 has been described in detail, it is to be understood that the automatic locking mechanism is useful in connection with the closure for any suitable dispensing receptacle. 10

The lid 5 is provided with dependent locking ears 11 and 12 over which the pivoted locking latch bolts 13 and 14 are pressed into locking engagement by their respective springs 15 and 16 upon the closing of the lid 5. 15

In the embodiment illustrated the locking latch bolts 13 and 14 form a part of the locking mechanism which is assembled within the box-like casing 16' which itself forms a closure for the parts at the rear of Fig. 1 and about the four edges but is open at the front and as shown in Fig. 4. A front closure for this box may be formed in any suitable manner. In the embodiment illustrated the front plate of the stamping 2 forms this closure inasmuch as the box 16' is secured to the inner side of the front plate 30 by rivets or screws 17. The construction is such that the entire locking mechanism may be completely assembled within the open faced box 16' before attachment to the wall of the receptacle 1. 35

40 The upper edge closure 18 of the box 16' is provided with a coin slot 19 alined with a coin slot 20 in the lid 5 when the lid is closed. This coin slot may be made of a size to prevent the passage therethrough of a coin larger than the proper one, such as 21, and its edge 22 forms a co-operating part in the locking mechanism as will presently be described.

A coin carrier 23 is provided for conveying the coin 21 away from the slot 19 and in this embodiment comprises a disk of sheet metal pivoted at its center to the stud 24 secured to the back of the box 16'. This disk 23 is provided with a coin pocket 25 of a size just sufficient to permit the entrance of the proper coin 21 and is arranged normally to lie in a position corresponding to that shown in Fig. 4 so that its shoulder 26 slightly projects across the coin slot 19 while the disk 23 is of a thickness corresponding to that of the proper coin and lies in the same plane as slot 19. The disk 23 is given a tendency to rotate in a counter-clockwise direction which, in this embodiment, is accomplished by means of the

spring 27 pressing the pivoted cam 28 against the cam roller 29 pivoted to the face of the disk 23.

When the parts are as shown in Figs. 1, 2, 3 and 4 the pivoted hook latch 30 prevents the counter-clockwise rotation of the disk 23 by hooking over the lip 31 formed at the periphery of the disk 23. The latch 30 is normally pressed toward the disk 23 by the spring 32. 75

The disk 23 is also provided with a cam 33 for co-operating with the downward projection or cam follower part 34 of the locking latch bolt 14. The portion of the periphery of the disk 23 lying between the follower part 34 and the cam 33 is circular and is indicated by 35 while the diametrically opposite portion 36 of the periphery is also circular. Occupying a clockwise displaced position from the shoulder 26 is a lip 37 having a generally circular contour but provided with finger engageable serrations 38 and an outstanding hip 39 at its end. This lip 37 serves as a closure for the coin slot 19 and the hip 39 as a stop, all as will presently be understood. 80

On the counter-clockwise side of the coin slot 19 is provided a fixed measuring barrier 40, the curved face of which clears the periphery of the disk 23 just a sufficient amount to permit the passage there-across of the projecting edge 41 of a coin of proper size, it being understood that the radial depth of the coin pocket 25 is insufficient to contain the inserted coin completely within the periphery of the disk 23 but causes it to project as shown in Fig. 6 so that its projecting edge 41 may operate as a cam to engage the heel 42 of the locking latch bolt 13. The disk 23 is also provided with a 95 detent notch 43 for co-operating with the nose 44 of latch 30 to prevent clockwise movement of the disk 23, under certain conditions. 100

Also centrally pivoted to the stud 24 is a mutilated disk 45, overlying the disk 23, permitted only a limited rotation about the stud 24 relatively to the disk 23, but otherwise free to rotate with the disk 23. One side of the disk is cut away to form the sector-like opening 46 which permits suitable play for the cam roller 29 and the cam 28 without interference with this overlying disk 45. The remainder of the periphery of this disk 45 is shown circular and concentric with the stud 24 except for the peripheral detent notch 47 exactly similar to the detent notch 43 of disk 23. A pin 48 is carried by the disk 45 and projects inwardly across the thickness of the disk 23 and, with the parts in normal position, occupies a position within the coin pocket 25 slightly to the left that is, toward the counter-clockwise direction from a line drawn through the stud 24 and the center of the coin slot 19. 110

An escape passage 49 is cut out of the disk 23 and opens into the coin pocket 25, as shown best in Fig. 5. It is arranged so as to permit the entrance of the pin 48 for a purpose presently to be described.

The disk 45 is also provided with notches 50 to provide for the operative engagement of a key, such as key 51, with the disk 45 to shift or retract it into position to discharge the coin 21 and to effect other movements of the disk 45 for purposes presently to be described. Of course these notches 50 should conform to the key employed or be substituted by any well known formation for key engagement.

Operation: Fig. 4 shows all the parts in normal position in which case the locking latch bolts 13 and 14 are in projected position to engage the locking ears 11 and 12 of a part such as the lid 5 to be locked closed.

The person desiring to remove the package 9 from the receptacle 1 inserts the proper coin 21 in the opening or slot 20 in the lid 5, pressing it down through the slot 19 which may be of an exact size to pass no larger coin than the proper one. Opposite portions of the edge of the coin engage respectively the edge 22 of slot 19 and the opposite shoulder 26 at the entrance of the coin pocket 25. Inward pressure upon the coin causes the coin to act as a wedge against the shoulder 26 to rotate the disk 23 clockwise into the position shown in Fig. 5. This rotation carries the lip 31 clear of the hooked end of latch 30. Continued inward pressure upon the coin thereupon causes the coin to engage the pin 48 and the wedging action takes place between the shoulder 26 and this pin 48 to effect a counter-clockwise rotation of super-posed disk 45 relatively to disk 23 so that the cam-like edge 53 on disk 45 wedges out the hooked end 44 of latch 30, the pin 48 passing into slot 49 and the latch 30 being rotated into the position shown in dotted lines in Fig. 5 and held clear of the lip 31. At this stage of the operation the coin 21 has become completely seated within the pocket 25 so as to clear the top wall 18 through which the coin slot 19 is formed. If the coin is of the proper diameter it just clears the barrier 40 and the two disks 23 and 45 rotate counter-clockwise with a quick snap-like action in response to the spring pressed cam 28 operating upon roller 29, which roller at the start of the operation described has served as a stop co-operating with the shoulder 54 of disk 45 to limit the clockwise position of pin 48 within the coin pocket 25. This counter-clockwise rotation carries the parts into the positions illustrated in Fig. 6, the position of this pin 48 being such that, by engaging the coin 21, it holds the disk 45 relatively to the disk 23 so that the two detent notches 43 and 47 are alined or super-posed to permit

the nose 44 of the latch 30 to spring and catch therein. The nose 44 cannot spring into either of these detent notches separately because of the fact that it is of a thickness sufficient normally to engage the peripheries of both the disks 23 and 45. The disk 23 is checked in its counter-clockwise rotation by the lip 39 engaging against the inside face of the wall 18, while the engagement of the latch 30 in the detent notch 43 locks the disk 23 against clockwise rotation. At the same time the latch 30 locks the disk 45 against a clockwise rotation but not against counter-clockwise rotation, a limited amount of which is permitted, according to the depth of the slot 49. The dotted lines in Fig. 6 show that the pin 48 may move counter-clockwise until it reaches the extremity of the slot 49.

The movement of the parts into the positions shown in Fig. 6 causes the projecting edge 41 of the coin 21 to engage the heel 42 of the pivoted locking bolt 13 to move it into unlocking position so as to disengage the ear 11. At the same time the cam 33 operates upon the follower part 34 of locking bolt 14 to move it into unlocking position in a similar manner. The operation of the coin 21 to unlock the bolt 13 is obviously that of a cam or striker required to be of definite dimensions to effect the complete throwing of the bolt into unlocking position although there is no structural limitation in the lock described necessitating that the coin 21 actually engage a part directly to release the bolt 13. The illustration of the cam 33 shows an embodiment in which the actual operating member is a permanent part of the mechanism instead of being the coin itself and obviously either one or the other of the locking bolts 13 and 14 could be used solely for locking the lid closed or a plurality of bolts like 14, operated each by a cam 33 suitably located might be employed, this alteration requiring nothing but mere duplication of parts.

It should be noted that the coin 21 has now been conveyed away from the coin slot 19 and that the coin slot 19 has been completely closed by the projecting lip 37 provided with the serrations 38. At the same time the coin is retained entirely within the locking mechanism, doing away with the necessity of a separate coin compartment. To restore the lock to normal condition and to effect the removal of the coin 21 a key such as the key 51 may be inserted through a suitable opening in the receptacle 1, which opening is indicated by 57 and may be of the contour illustrated to give the false impression that a key provided with a tongue is the kind necessary for removing the coin. The key 51 is first rotated counter-clockwise and its engagement with the disk 45 causes a corresponding counter-clockwise rotation of

this disk 45 to wedge out the nose of the latch 30 into the position shown in Fig. 7. This counter-clockwise rotation is limited by the movement of the pin 48 in the slot 49 or by the nose 53 engaging the cam 28. The disk 45 is so loosely pivoted that the moment the key 51 is removed or if a counter-clockwise turning moment is not applied to the key 51 the force of the spring 32 will cause the nose 44 of latch 30 to engage the curved shoulder 58 with sufficient force to retract the disk 45 into the position shown in Fig. 6 causing a relocking of both disks by the latch 30. Therefore, while the disk 45 is held by the key in the position shown in Fig. 7 a finger 59 should engage the serrated portion 38 of the disk 23 and exert a force in the direction of the arrow (applied to the finger), which will cause the shoulder 60 to engage the nose of latch 30 and hold it in the position illustrated in Fig. 7. The key 51 is then given a clockwise rotation which carries the shoulder 61 of disk 45 and then the periphery of disk 45 under the nose of the latch 30 to hold it positively in the position illustrated. The pin 48 engages the coin 21 and the continued clockwise rotation of disk 45 imparts a continued clockwise rotation to the coin carrier or disk 23 until the coin pocket 25 has been moved into the position shown in Fig. 5. When in this position the coin slot 19 is directly in line with the mouth of the coin pocket 25 and the force of the pin 48 directed against the edge of the coin 21 tends to wedge it out of the coin pocket into the slot 19. The shoulder 26 also co-operates in this wedging action so that the coin is wedged out through the slot 19 into the position shown in Fig. 5 where it is easily grasped in the fingers and removed. Too great a clockwise movement of the disk 23 is prevented by the rear edge 62 of cam 33, the path of which for such rotation would carry it against the nose of latch 30. Upon the withdrawal of the coin 21 the cam 28 causes the counter-clockwise rotation of disk 23 into the position shown in Fig. 4 causing the hooked nose of latch 30 to hook over the projection 31, locking the disk 23 against operative rotation until another suitable coin has been inserted.

It will, of course, be understood that applicant's novel feature of returning the deposited coin or check through the coin-entrance slot of the lock, may be mechanically carried out in other ways than that herein shown and described by way of illustration. In the broad aspect of my invention as regards this particular feature, as brought out in certain of the appended claims, the form and manipulation of the means for discharging the coin out of its seat in the coin-carrier through the coin-entrance slot may be modified or altered

without departing from the scope of my invention as defined in those claims.

The hook formation of the latch 30 in its co-operation with the lip 31 plays an important function in preventing the unauthorized releasing of the coin carrier 23, the release of which is effective in unlocking the locking bolts 13 and 14. Should a tool, such as a knife blade, be inserted through the coin slot 19 and force applied thereby to the pin 48 tending to cause a counter-clockwise rotation of the disk 45, the nose 53 of disk 45 would engage the hooked end 44 of latch 30. This nose 53 would tend to rotate the latch 30 away from the disk 23, but the end 80 of the nose 44 hooked over the lip 31 effectively locks the latch 30 against release, which would not be the case if the latch 30 would not hook over a suitable part fixed to or on the disk 23, such as the lip 31. 85

Although the embodiment of the invention illustrated shows a coin carrier 23 having a rotary movement, the coin pocket 25 therein causes the coin to slide from one position to another and it is well contemplated by the applicant that many features of the applicant's invention are not limited in their embodiment to a lock mechanism comprising a rotatable disk for the coin carrier or a rotatable disk for locking purposes. 95 However, the embodiment illustrated and described serves its purpose of illustrating a satisfactory embodiment of the features of the invention.

What is claimed and what is desired to be 100 secured by United States Letters Patent is:—

1. In a coin-operated lock, the combination with a movable locking bolt, of a rotatable coin-carrier for receiving the coin through a suitable entrance opening; means for rotating the coin carrier to convey the coin away from said opening and to effect the movement of said bolt into unlocking position; latching means for locking the coin carrier in operated position to prevent the withdrawal of the coin; and key actuated means for releasing said latching means to permit rotation of said coin-carrier back to normal position to carry the coin back into said coin-entrance opening for ready removal. 110

2. In a coin-operated lock, a casing; a rotatable coin carrier having a coin pocket; means wholly within said casing for rotating said carrier to convey said coin pocket into closed position within said casing; means adapted to engage said coin-carrier for locking said coin pocket in said closed position; a locking bolt for a receptacle closure; means actuated by the movement 120 of said coin carrier for moving said bolt into unlocking position; and means for unlocking said coin carrier to permit the retraction of the parts. 125

3. In a coin-actuated lock, one or more 130

bolts normally in locking position; a wall providing a coin slot; bolt actuating mechanism having spring means tending to cause movement to unlock each of said bolts; latch mechanism holding said bolt actuating mechanism against unlocking movement; and means operated by the insertion of the proper coin through said slot to release said latch mechanism to cause the automatic unlatching of said bolts without other manual manipulation.

4. In a coin-actuated lock, a wall providing a coin slot; movable means for automatically conveying the proper coin inserted through said slot away from said slot; means for closing said coin slot; and bolt releasing mechanism automatically operated in response to the insertion in said coin slot of the proper coin without the manual manipulation of other parts.

5. In a coin-operated lock, a closure; spring actuated means releasable upon the insertion of the proper coin and automatically movable when released to secure said coin within the lock; and locking means for said closure automatically unlocked by said spring actuated means by reason of the said movement thereof.

6. In a coin-operated lock, a casing provided with a coin-entrance slot, a coin-carrier mounted within said casing and having a coin-pocket, means wholly within said casing for moving said coin-carrier in one direction to secure a deposited coin within said lock, said coin-carrier being movable in the opposite direction to discharge the coin through said slot, and mechanism for effecting the discharge of the coin through said slot, said mechanism requiring the joint actuation of a key and a finger manipulation of said coin-carrier.

7. In a coin-operated lock, a coin carrier comprising a centrally pivoted disk having a coin pocket open at the periphery of said disk; spring means tending to rotate said coin carrier; a latch operating to hold said coin carrier against rotation; a rotatable part having a pin projecting into said coin pocket and operative to release said latch upon the entrance of the proper coin into said coin pocket to wedge over the said pin; and bolt releasing means operated by the rotation of said coin carrier.

8. In a coin-operated lock, a closure; spring actuated means releasable upon the insertion of the proper coin and automatically movable when released to secure said coin within the lock; and locking means for said closure automatically unlocked by said coin upon the said movement of said spring actuated means.

9. In a coin-operated lock, a closure; a spring actuated rotatable means adapted to be released upon the insertion of the proper coin and automatically movable when re-

leased to carry said coin within the lock; and locking means for said closure automatically unlocked by said rotatable means during the said movement thereof.

10. In a coin-operated lock having a coin-entrance slot, a locking member, coin-controlled mechanism for controlling the operation of said member, said mechanism having a pair of elements disposed in the path of the entering coin and adapted to be actuated thereby, and means for actuating said mechanism after action of the coin upon said elements.

11. In a coin-operated lock having a coin-entrance slot, a rotatable coin-carrier adapted to receive the coin or check inserted through said slot, manually operable means whereby the coin or check in said carrier is discharged from the lock through said coin-entrance slot, and means independent of said discharging means for operating said coin-carrier to carry the deposited coin into operative position in the lock.

12. In a coin-operated lock having a coin-entrance slot, a rotatable member arranged in proximity to said slot and having a portion adapted to engage the entering coin, so that the forcing of the coin into the slot rotates said member, a locking device, and means controlled by said rotatable member for controlling the operation of said locking device.

13. In a coin-operated lock having a coin-entrance slot, a locking member, a pair of movable members adapted to be simultaneously engaged by the entering coin and moved relatively to each other, means within the lock for automatically actuating said coin-connected members to operate said locking member, said members retaining the deposited coin in operated position, and means to cause reverse operation of said members for discharging the coin through said slot.

14. In a coin-operated lock having a casing provided with a coin-entrance slot, a rotatable coin-carrier mounted within said casing and adapted to secure the deposited coin within the lock, and means whereby said coin-carrier is rotatable within said casing to discharge the coin through said coin-entrance slot.

15. In a coin-controlled lock having a coin-entrance slot, a pair of concentric disks movable relatively to each other, a device for normally locking said disks, co-operating means on said disks adapted to be engaged by the entering coin to cause release of said locking device, and spring-actuated mechanism adapted to automatically operate the coin-released disks.

16. In a coin-operated lock having a coin-entrance slot, a rotatable coin-carrier adapted to secure the deposited coin within said lock by movement in one direction, and

- means whereby said coin-carrier is rotatable in the reverse direction to discharge the coin through said coin-entrance slot.
17. In a coin-operated lock having a casing provided with a coin-entrance slot, a locking member, a normally locked coin-carrier, mounted wholly within said casing, means whereby said coin-carrier is released for operation by the mere insertion of the 10 coin, spring mechanism within said casing for automatically actuating the released coin-carrier to operate said locking member, and means for retaining the coin on said carrier after operation thereof.
18. In a coin-operated lock having a coin-entrance slot, a pair of relatively movable members, means for normally locking said members against operation, coöperating means on said members adapted to be engaged by the entering coin to cause release 20 of said locking means, and mechanism for actuating the coin-released members, said members retaining the deposited coin in their operated position.
19. In a coin-operated lock having a coin-entrance slot, a latch device normally held in locking position, mechanism normally held locked against movement by said latch device and adapted to retain the same in 30 locking engagement therewith, said mechanism being adapted to be operated through the medium of the coin to release said latch device for movement into unlocking position, means for moving the released latch device into unlocking position, and means for actuating the released mechanism.
20. In a coin-operated lock, a casing having a coin-entrance slot, a rotatable disk provided with a coin-receiving slot or recess, means manually operable from the outside of said casing for moving the coin out 40 of said coin-receiving slot or recess to discharge the same through said coin-entrance slot, and means independent of said dis-

charging means for operating said disk to 45 carry the deposited coin into operative position in the lock.

21. In a coin-operated lock having a coin-entrance slot, a normally locked coin-carrier, means for releasing said coin-carrier 50 through the medium of the deposited coin, mechanism for actuating the released coin-carrier, means for locking said coin-carrier in operated position to retain the coin, key-controlled means to release the coin-carrier 55 in its operated position, and means on said coin-carrier adapted to project out of said coin-slot when the carrier is in operated position to permit finger manipulation of the released coin-carrier for discharging the 60 coin through said slot.

22. In a coin-operated lock having a coin-entrance slot, a member adapted to receive the deposited coin and carry the same away 65 from said slot, means for actuating said member, and means on said member adapted to project out of the coin-entrance slot when the member is in operated position to permit finger manipulation of said member to discharge the deposited coin through said slot. 70

23. In a coin-operated lock having a coin-entrance slot, a rotatable disk provided with a coin-receiving slot or recess, a member adapted to be moved upwardly through said coin-receiving slot or recess to engage the 75 deposited coin and push the same upwardly through said coin-entrance slot, and means independent of said member for operating said disk to carry the coin into operative position in the lock.

In witness whereof, I have signed my name to this specification, in the presence of two subscribing witnesses.

DENYS W. CORBET.
